(57) CLAIM

The ornamental design for a wellness ball, as shown and described.

DESCRIPTION

FIG. 1 is a perspective view of a wellness ball, the perspective view partially from the front of the wellness ball, partially from a left side of the wellness ball, and partially from a top of the wellness ball;

FIG. 2 is a front view of the wellness ball of FIG. 1; and, FIG. 3 is a top view of the wellness ball of FIGS. 1.

The broken lines in the embodiments of FIG. 3 are provided for context only, and form no part of the present design.

1 Claim, 3 Drawing Sheets

FIG. 1

FIG. 3
